GRASS SHEARS

Henry R. Winogrond, Watertown, Wis., assignor to The Village Blacksmith Co., a corporation of Wisconsin

Application October 25, 1955, Serial No. 38,573

Term of patent 14 years

(Cl. D22—5)

I claim:

The ornamental design for grass shears, as shown.
